US0D1051219S

(12) **United States Design Patent** (10) **Patent No.:** **US D1,051,219 S**
(45) **Date of Patent:** **** Nov. 12, 2024**

(54) **3D PRINTER**

(71) Applicant: **Shenzhen Elegoo Technology Co., Ltd.**, Shenzhen (CN)

(72) Inventor: **Biao Liu**, Shenzhen (CN)

(***) Term: **15 Years**

(21) Appl. No.: **29/930,385**

(22) Filed: **Feb. 29, 2024**

(30) **Foreign Application Priority Data**

Dec. 14, 2023 (CN) 202330822782.7

(51) **LOC (14) Cl.** **15-09**

(52) **U.S. Cl.**

USPC **D15/122**

(57) **CLAIM**

The ornamental design for a 3D printer, as shown and described.

DESCRIPTION

FIG. 1 is a front elevation view of a 3D printer showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is an enlarged view of the encircled portion in FIG. 7.

The broken lines depict portions of the 3D printer that form no part of the claimed design. The dash-dot lines in FIG. 7 and FIG. 9 illustrate the enlarged view indicators and form no part of the claimed design.

1 Claim, 9 Drawing Sheets
